8 Claims

ABSTRACT OF THE DISCLOSURE

A package of hair curlers. The curlers are axially compressible, for example, coil springs having sides covered with a netting. In the package the curlers are held in axially compressed condition. The invention also provides a clip for holding the curlers.

This application is a continuation of application Ser. No. 656,424 filed July 27, 1967, now abandoned.

BACKGROUND OF THE INVENTION

Hair curlers in the form of cylinders, for example 1½" diameter by 3" long, are in widespread use. From 5 to 15 curlers are commonly included in a set for one setting of the hair, and a problem arises by reason of the bulk of the set when traveling. For short trips, a small overnite bag may be ample for personal effects other than the curlers, but commonly is of insufficient size to permit taking the number of curlers desired.

The present invention has as its objective providing means for storing a set of hair curlers in a small package.

SUMMARY OF THE INVENTION

The invention particularly contemplates axially compressible curlers, such as the known coil springs covered with netting. A package is formed of the curlers and means holding the curlers in axially compressible condition.

In a preferred embodiment, the invention provides a clip comprising an elongated member, a base member, and a top member. The base member is secured to one end of the elongated member and extends lengthwise transversely of the elongated member and radially outwardly thereof. The top member includes means movable relative to the elongated member between a first position permitting moving of open ended elongated elements of diameter less than the length of the base member, coaxially onto the elongated member and a second position in which the top member is disposed transversely of the elongated member and extends radially outwardly thereof for locking the elongated elements on the elongated member between the base member and the top member. The elongated elements, e.g. hair curlers, are cylindrical coil springs, and a plurality of the curlers can be stored on the clip, in compressed condition, with the base member and the top member holding the curlers in this condition.

BRIEF DESCRIPTION OF THE DRAWINGS

The invention is illustrated in the accompanying drawings wherein:

FIG. 1 shows a clip according to the invention;

FIGS. 2-4 show an embodiment of the combination of the invention including clips and hair curlers;

FIG. 5 shows a U-shaped element for use as the elongated member;

FIG. 6 shows a portion of a hair curler; and

2

DESCRIPTION OF PREFERRED EMBODIMENTS

Referring to FIG. 1, the clip comprises the elongated member 10, which is a generally U-shaped wire. A base is provided by the outturned free ends 11, and a holder 12 is secured to the other end of the clip. A loop 14 is formed in the transverse section of the U-shaped elongated member, and a complementary loop 15 is formed in the holder 12. The loops 14 and 15 interengage, so that the holder 12 is movably positioned on the U-shaped 10 elongated member. The holder 12 can be shifted so that hollow cylindrical articles of diameter not greater than the width w of the U-shaped member, can be passed over the transverse end of the U-shaped member, and positioned along the U-shaped member between the base 15 thereof formed by the outturned ends 11, and the holder 12. The diameter of the hollow cylinders is less than the length of the base member and the length of the holder, and upon shifting of the holder to a direction transverse to the U-shaped elongated member 10, these 20 cylinders are secured on the clip.

Referring to FIGS. 2-6, a box 16, which can be of any suitable material, for example metal or molded plastic, comprises end 18, to which elongated members 20 and 21 are pivotally connected at, respectively, 24 and 25. Box end 17 has a lip 22 extending inwardly toward the pivot mountings, and terminating a short distance from end 17. The elongated members 20 and 21 trace the arcs 23 upon being pivoted between a lowered and a raised position. The radius of this arc is such that the free 30 ends of the elongated members clears the lip 22 so that the free ends can be moved into and out of the box.

The hair curlers can be coil springs covered with netting. In FIG. 6, a portion of such a hair curler is depicted. The curler 26 includes the coil spring 27, covered 35 with netting 28. The netting includes inturned ends 29 which turn back over the ends of the coil, extend axially inwardly a short distance and then terminate. A hair curler of the type shown in FIG. 6 is preferred. However, any axially compressible curler can be used.

Referring to FIG. 4, the hair curler 26 can be moved in the direction of the arrow 31 to dispose it along the elongated member 21, coaxially therewith. A plurality of the curlers can be placed along the elongated member, and the curlers can be axially compressed. The elongated 45 member can then be pivoted downwardly to dispose the curlers within the box. A plurality of axially compressed curlers 30 is shown in FIG. 4, mounted on the elongated member 20. The end curler 30a has one end thereof disposed over the elongated member 20, and the other end thereof extending outwardly of the free end of the elongated member. The outer end of curler 30a, i.e. said other end, is disposed under the lip 22. Due to the compressed condition of the curlers, the outer end of curler 30a is urged into engagement with the box end 17, and the lip 22 50 prevents pivoting of the elongated member 20, so that the curlers 30 are secured within the box. When it is desired to remove the curlers, the curlers can be axially compressed to move the outer end of curler 30a so that it clears the lip 22, and the elongated member 20 with the curlers thereon can then be pivoted so that the curlers 55 are lifted out of the box.

Instead of the lip 22, any suitable catch means can be employed. Such means can be for engagement of the outer end of the curler 30a to secure the elongated member with the curlers mounted thereon against pivoting on the base member. Such catch means is further for disengagement with the outer end of the curler 30a, by axially compression of the curlers, permitting pivoting of the elongated member on its pivot mounting. The catch means can be, for example, a hook secured to the bottom of the box to releasably engage the outer end of curler 70

30a. Alternatively, the box can be provided with a movable top which secures the curlers in place.

An enlarged view of the elongated member is shown in FIG. 5. This member is a U-shaped element 32 having inturned ends 33, which can be pivotally mounted in a container or holder for the curlers. Preferably, the width w of the U-shaped member is substantially equal to the inside diameter of the hair curlers. This assures a good fit of the curlers on the elongated member with the curlers held coaxial with the elongated member.

In the embodiment of FIG. 2, the box end 18 is joined to the box end 17 by the bottom 19 of the box, so that these elements, the ends and the bottom of the box, form a channel shaped structure, with the end 18 being one of the channel flanges, and the end 17 being the other channel flange.

If desired, the box can be provided with a cover.

Any number of elongated members can be used. If desired, but a single elongated member can be used. For a set of curlers including from about 10-15 members, it has been found that the use of two elongated members is desirable. There is some tendency for the curlers to spring off the elongated member during removal, and by limiting the number of curlers on an elongated member, inconvenience occasioned by the springing off of curlers can be reduced or avoided. From 4-7 on an elongated member is preferred.

The size of the curlers, in uncompressed condition, can be from $1\frac{1}{2}$ " to 2" in diameter, usually 1" to $1\frac{3}{4}$ " in diameter, and the length can be 1" to 3", usually $1\frac{1}{2}$ " to $2\frac{1}{2}$ ". The coil springs can be formed of any suitable metal.

The netting 28 over the coil spring can be formed of plastic treads. It is surprising that though the inturned ends 29 are free within the spring, placement and removal of the curlers does not cause any significant displacement of the free ends of the netting.

If desired, in marketing, the combination of the curlers and clip or box can be sold together but with the curlers not held in compressed condition. This may be in order, depending on the characteristics of the axially compressible member, e.g. the characteristics of a particular coil spring, to insure against a permanent deformation of the material as would reduce the extent to which the compressible member elongates upon release from the compressed condition.

While the invention has been described with respect to particular embodiments thereof, these embodiments are merely representative, and do not serve to set forth the limits of the invention.

What is claimed is:

1. In combination axially compressible hair curlers and a holder therefor:

(a) said holder comprising:

(1) a channel shaped structure, one channel flange forming a base member, the other channel flange forming a top member, the channel body portion integrally joining the base member and the top member;

(2) an elongated member pivotally mounted on the base member for movement between a first position in which the free end of the elongated member is disposed outwardly of the channel structure for receiving and removal of hair curlers and a second position in which the elongated member is disposed within the channel structure for storage of hair curlers disposed on the elongated member with the base member and the top member retaining the curlers on the elongated member.

(b) a plurality of hair curlers disposed on the elongated member with the elongated member in said second position; said curlers being held in axially

compressed condition by said base member and said top member;

(c) the free end of the channel flange forming the top member comprises a lip extending toward the channel flange forming the base member, said lip terminating short of the arc of the elongated member upon pivoting thereof on said pivot mounting on the base member,

(d) said axially compressed hair curlers including an axially compressed curler disposed with one end thereof over the free end of the elongated member and the other end thereof beneath said lip.

2. The combination of claim 1, wherein the hair curlers are coil springs covered with netting.

3. Combination according to claim 2, said elongated member being U-shaped with its free ends pivot mounted to provide said pivot mounting, the width of the elongated member being about equal to the diameter of the curlers.

4. Combination according to claim 3, said netting including inturned ends disposed within the coil springs.

5. In combination axially compressible hair curlers and a holder therefor:

(a) said holder comprising:

(1) a channel shaped structure, one channel flange forming a base member, the other channel flange forming a top member, the channel body portion integrally joining the base member and the top member;

(2) an elongated member pivotally mounted on the base member for movement between a first position in which the free end of the elongated member is disposed outwardly of the channel structure for receiving and removal of hair curlers and a second position in which the elongated member is disposed within the channel structure for storage of hair curlers disposed on the elongated member with the base member and the top member retaining the curlers on the elongated member.

(b) a plurality of hair curlers disposed on the elongated member with the elongated member in said second position; said curlers being held in axially compressed condition by said base member and said top member;

(c) said axially compressed hair curlers including an axially compressed curler disposed with one end thereof over the free end of the elongated member and the other end thereof extending axially outwardly of the free end of the elongated member,

(d) and catch means for engagement with said other end of the last mentioned curler securing the elongated member with curlers mounted thereon against pivoting on the base member, and dis-engagement with said other end of the last mentioned curler by further axial compression of the curlers, permitting pivoting of the elongated member on its pivot mounting.

6. The combination of claim 5, wherein the hair curlers are coil springs covered with netting.

7. Combination according to claim 6, said elongated member being U-shaped with its free ends pivot mounted to provide said pivot mounting, the width of the elongated member being about equal to the diameter of the curlers.

8. Combination according to claim 7, said netting including inturned ends disposed within the coil springs.
